JIG FOR MOUNTING SPLIT PATTERNS

Albert Turner, Siles, Pa.

Application September 8, 1932, Serial No. 632,265

8 Claims. (Cl. 22—191)

(Granted under the act of March 3, 1883, as
amended April 30, 1928; 370 O. G. 757)

This invention relates to means for fixing the positions of the parts of a split pattern upon a pattern board, and has for its object to provide a device of the type specified that will make it possible for even an unskilled person to place properly the parts of a split pattern so that when the drag and the cope of the flask are assembled, the parts of the mold will fit together with a high degree of accuracy.

10 With the above and other objects in view, the invention consists in the construction, combination and arrangement of parts as will be described more fully hereinafter.

In the drawings:

15 Fig. 1 is a perspective view of my invention showing the jig in position on a pattern board to mark dowel holes for one-half of a pattern;

20 Fig. 2 shows the jig in position to mark the dowel holes for the said other half, the holes marked in the first position being shown;

Fig. 3 is a perspective view of the halves of a pattern in place upon the pattern board.

Heretofore the use of patterns mounted on follow-boards has been restricted because of the difficulty and cost of so arranging the pattern on the board that when the cope and the drag that have been molded from one pattern are assembled, they will match together perfectly. This difficulty is comparable to making the outlines of the right hand and the left hand upon the right-hand and left-hand pages of a book so that when the book is closed the two outlines will coincide.

In previous methods of placing the parts, the pattern lines fixing the positions thereof must be laid down on the board so that the mold made therefrom will match without overlapping at any place, since if they do not so match, the mold cannot be used. The lines so laid down must be placed very accurately as any error therein produces twice that error in the mold. This can be done only by a person highly skilled and requires much time.

With my invention the patterns can be placed with perfect accuracy by an unskilled person and with a saving in time of from fifty to ninety percent.

The jig comprises side rails 4 to which is rigidly fixed an end member 5 having in it holes 6 through which the flask pins 7 may be passed, a movable end member 8, a frame brace bar 29, and movable bars 9, 10 and 11 having in them series of holes 12, 13 and 14 of different sizes to accommodate pattern dowel pins of different

Movable end member 8 consists of a main member at each end of which the pieces 15 are secured to the sides thereof, leaving between them a space in which the side-rails can easily slide. A screw 16 passes through one of the pieces 15 at each end and is threaded into the other piece 15 whereby the pieces 15 can be drawn together and clamped upon the side rails. The construction of frame brace bar 29 is similar to that of end member 8 except that it does not have in it holes for the 10 flask pins. The end members have in them threaded holes 17 to receive threaded pegs 18 that may be screwed in to touch flask pins 7 to allow the pins to slide readily but without play in order to position the jig accurately with respect to the flask pins.

Movable bars 9, 10 and 11 are double, the two parts of each being secured together by screws 19 adjacent their ends that can be tightened to clamp the bars in position where set, or loosened to permit moving the bars on side rails 4.

The method of use is as follows:

Movable end member 8 is set with the centers of holes 6 therein a distance from the centers of holes 6 in fixed end member 5 equal to the distance between the centers of the flask pins 7 on follow board 20 and the jig is set on the board with the flask pins 7 through holes 6; pegs 18 are set lightly against the flask pins so that the jig may be readily lifted off the pins 7 but longitudinal movement of the jig is prevented. Movable bars 9, 10 and 11 are then shifted so that holes adapted to the size of the pattern dowel pins are in position to have the dowels passed through them and screws 19 are tightened to hold the bars in place; in Figs. 1 and 2 these holes are indicated by 14'. The jig, with the pattern on it, is lifted from the flask pins and the holes through which the dowels pass are marked. The pattern is then removed, the jig replaced on the flask pins, and holes bored into the board through the marked dowel pin holes, the double bars serving as a guide to insure that the drill will be kept perpendicular to the board. If the pattern halves are to be disposed side by side transversely of the board, the jig is then turned upside down about its longitudinal axis; if they are to be arranged on a line in the other dimension of the board, the jig is turned over about a transverse axis. In either case, the flask pins are passed through the holes in the end members used in the first position and holes are formed in the board through the same dowel pin holes in the movable members, the two groups of holes thus formed having a relation of bilateral symmetry. Thus the parts 21

and 22 of the pattern are disposed in the relative positions of an object and its mirror image when the dowel pins of the parts are inserted in the holes in the pattern board, as is shown in Fig. 3.

5 5. By making on the board, as shown in Fig. 3, one-half the mold in the cope and the other half in the drag, two molds are made in one flask, which match perfectly.

If desired, to fit any particular flask, the movable bars 9, 10 and 11 can be removed from the side rails and slidably mounted on the end members or an end member and frame brace 29, with the movable end member 8 and/or the brace set in a suitable position.

10 15. The positions of the flask pins 7 can be fixed to suit any requirement by setting the end member 8 in the proper position, making holes in the board corresponding to suitable holes 6 in the end members and setting the flask pins in those holes.

20 20. With this device it is as easy to mount the most intricate pattern as to mount the simplest kind. If the board must be used for another pattern before finishing with one mounted thereon, the pattern can be removed and later quickly replaced

25 25. without inaccuracy, whereas if the pattern had been mounted by means of lines on the board, they would have been obliterated and the second setting of the pattern would consume as much time as the first. If two boards are used, one for 30 each half of a pattern, it is merely necessary to set the flask pins on the two at equal distances and use the jig the same as when but one board is involved.

35 Additional advantages accruing from the use of my invention are:

It obviates the necessity of a trial pouring to determine if the parts of the mold are matched;

It eliminates almost entirely the parting line on the casting;

40 Practically eliminates the necessity for hand ramming of the mold as an alternative to machine ramming where the principal ground for choice between them is based on the cost of mounting the parts of the pattern on the board;

45 Makes possible machine ramming of molds that would ordinarily require six men if done by hand. It is, of course, well known that machine ramming is not only more rapid and cheaper than hand ramming, but the compacting of the sand 50 in the mold is much more uniform and satisfactory when machine ramming is used.

55 As a concrete example of the saving in time effected by the present invention, split patterns that require two to eight hours to mount by the use of lines on the board can be mounted by means of the jig in fifteen to sixty minutes.

The invention herein described may be manufactured and used by or for the Government of the United States of America for governmental purposes without the payment of any royalties thereon.

I claim:

1. As an article of manufacture, a jig comprising side rails, an end member fixed thereto, a 65 movable end member slidably on said rails and having means to clamp it in position on the rails, both end members having holes to receive flask pins and means to position the flask pins in the holes, a frame brace slidably on the rails and having means to clamp it in place thereon, and a plurality of movable members, each said 70 movable member including bars disposed one on each side of both of said rails and means to clamp the two bars of each member against the rails, 75 each of said movable members having through

both bars thereof a plurality of series of registering holes of different sizes to receive the dowel pins of the parts of a split pattern and to serve as guides in making holes in a pattern board in positions corresponding to the positions of said 5 dowel pins.

2. As an article of manufacture, a jig comprising side rails, an end member fixed thereto, a movable end member slidably on said rails and having means to clamp it in position on the rails, both end members having holes to receive flask pins and means to position the flask pins in the holes, and a plurality of movable members, each movable member including two bars disposed one on each side of both of said rails and means to clamp the two bars of each member against the rails, each of said movable members having through both bars thereof a plurality of series of registering holes of different sizes to receive the dowel pins of the parts of a split pattern and to serve as guides in making holes in a pattern board in positions corresponding to the positions of said 10 dowel pins.

15 3. As an article of manufacture, a jig comprising side rails, an end member fixed thereto, a movable end member slidably on said rails and having means to clamp it in position on the rails, both end members having holes to receive flask pins, and a plurality of movable members, each movable member including two bars disposed one 20 on each side of both of said rails and means to clamp the two bars of each member against the rails, each of said movable members having through both bars thereof a plurality of series of registering holes of different sizes to receive the dowel pins of the parts of a split pattern and to serve as guides in making holes in a pattern board in positions corresponding to the positions of said 25 dowel pins.

30 35 4. As an article of manufacture, a frame including end members and side members, said end members having holes therethrough to receive flask pins, and a plurality of movable members slidably on frame members and adapted to be clamped in position thereon, said movable members having a plurality of series of holes of different sizes to receive the dowel pins of the parts of a split pattern and to serve as guides in making holes in a pattern board in positions corresponding to the positions of the dowel pins. 40

45 5. As an article of manufacture, a frame including end members and side members, said end members having holes therethrough to receive flask pins, and a plurality of movable members slidably on frame members and adapted to be clamped in position thereon, said movable members having a plurality of holes of different sizes therethrough to receive the dowel pins of the parts of a split pattern and to serve as guides in making holes in a pattern board in positions 50 corresponding to the positions of the dowel pins. 55

6. In a device of the class described, adjustable members having holes to receive the dowel pins of the parts of a split pattern whereby the said members are positioned, means to fix the adjustable members in the respective positions determined by said dowel pins whereby the holes through which the dowel pins pass may serve as guides for making holes in a pattern board in positions corresponding to the positions of said 65 dowel pins, the said holes being adapted to receive the dowel pins in mounting the pattern on the pattern board.

7. In a device of the class described, a frame having a plurality of sides, there being holes in 70 75

certain of said sides to receive the pins of molding flasks, double members movably mounted on two of said sides and adjustable through a considerable range of angularity with respect to 5 said sides, there being a plurality of series of holes of different sizes through said double members to receive dowel pins of the parts of a split pattern whereby the positions of said members for any pattern are determined and means to fix said 10 double members relatively to each other and to the sides.

8. A method of determining the position of the parts of a split pattern on a pattern board,

comprising the steps of fixing the positions of a plurality of points to correspond to previously fixed relative positions of the dowel pins of a half of a split pattern, forming a group of holes to receive dowel pins in conformity with the said points, forming another group of holes in conformity with said points but in relative positions having a relation of bilateral symmetry to the aforesaid holes, and mounting the two halves of the pattern with the dowel pins thereof 10 in the said groups of holes.

ALBERT TURNER.
